(57) **CLAIM**

The ornamental design for a hook and loop fastener patch pattern, as shown and described.

DESCRIPTION

FIG. 1 is a front perspective view of a hook and loop fastener patch pattern showing our new design;

FIG. 2 is a rear perspective view of the hook and loop fastener patch pattern shown in FIG. 1;

FIG. 3 is a front elevational view of the hook and loop fastener patch pattern shown in FIG. 1;

FIG. 4 is a rear elevational view of the hook and loop fastener patch pattern shown in FIG. 1;

FIG. 5 is a left-side elevational view of the hook and loop fastener patch pattern shown in FIG. 1;

FIG. 6 is a right-side elevational view of the hook and loop fastener patch pattern shown in FIG. 1;

FIG. 7 is a top plan view of the hook and loop fastener patch pattern shown in FIG. 1; and,

FIG. 8 is a bottom plan view of the hook and loop fastener patch pattern shown in FIG. 1.

The broken lines shown in the drawings represent portions of the hook and loop fastener patch pattern that form no part of the claimed design.
